UNITED STATES PATENT OFFICE.

WILLIAM H. SAUVAGE, OF FLUSHING, NEW YORK, ASSIGNOR, BY MESNE ASSIGNMENTS, TO GOULD COUPLER COMPANY, OF NEW YORK, N. Y.

SLACK ADJUSTER.

Application filed February 6, 1920. Serial No. 356,753.

To all whom it may concern:

Be it known that I, WILLIAM H. SAUVAGE, a citizen of the United States, residing at Flushing, Long Island, in the county of 5 Queens and State of New York, have invented certain new and useful Improvements in Slack Adjusters, of which the following is a specification.

This invention relates to improvements in 10 slack adjuster mechanisms and more particularly that type of slack adjuster mechanism adapted to be associated with the foundation brake rigging of railway vehicles.

One of the objects of the present invention is to provide a reliable and efficient slack adjuster mechanism particularly adapted for use in connection with the foundation brake rigging and which will insure 20 the taking up of all excess travel in the entire brake rigging of each car on each application and release of the brakes.

A further object is to provide improved mechanism of the above general character of 25 simple and practical construction which may be operated either by hand or power brakes.

A further object is to provide an improved mechanism of the above character which is applicable not only to the foundation brake 30 rigging of all railway vehicles but may also be applied to the brake rigging of four wheel street cars and the like without material modification.

Other objects will be in part obvious and 35 in part hereinafter pointed out in the accompanying sheets of drawings wherein one of various possible embodiments of the present invention is shown and in the several views of which similar reference characters 40 denote corresponding parts.

Figure 1 is a plan view of the brake cylinder and such parts of the brake rigging as are necessary to understand the invention;

Figure 2 is an elevational view thereof; 45 and

Figure 3 is a detail view of an adjusting rod.

Referring now to the drawings in detail, in which like reference characters denote 50 like parts, 5 denotes a brake cylinder provided with a piston 6 pivotally connected at 7 to the upper end of a live lever 8 which is pivotally connected at its lower end with a shackle 9 whereby it is further pivotally

connected at 13 with one end of a second 55 live lever 14. The opposite end of the cylinder is provided with a fixed support 10 to which is pivotally connected at 11 the upper end of a dead lever 12 which is pivotally connected through a shackle 15 to a second 60 dead lever 16.

The live and dead levers 14 and 16 are connected near their central parts at 17 and 18, respectively, with the two parts of the telescopic push rod 20 and 21. The tubular 65 member 21 is provided with a housing 22 within which is located any desired form of positively acting permanent take-up and holding means, such as dogs 23 as shown in Figure 2. These dogs are held in canted engagement with rod 20 to prevent a relative inward movement or shortening of rod 20, 21. Near the opposite ends of the live and dead levers 14 and 16 is a second connecting member comprising a rod 24 having a slotted 70 or lost motion connection 25 with the dead lever, said rod telescoping with the tubular member 26 pivotally connected at 27 with the live lever 14. The extreme ends of the live and dead levers are connected with a 75 coil return spring 28 provided with threaded adjusting means 30 at each end whereby its tension may be varied as circumstances require. The adjusting rod comprising the members 24 and 26 is also provided within 80 the housing 31 with any desired form of positively acting temporary take-up and holding means such as dogs and springs similar to the dogs 23 and spring 29 of Figure 2. The dogs in this housing 31 are 85 canted against rod 24 to prevent a relative inward movement, or shortening, of rod 24, 26. Both rods 20, 21 and 24, 26, however, are free to move in a relative outward direction, that is, to greater effective length, being loosely engaged with respect to the holding dogs for movement in that direction. 90

As herein shown, these ends of the live and dead levers are connected by means of struts 32 with brake beams or other desired 100 form of power transmitting means according to the particular application to which this form of slack adjuster is put.

It will be noted that the rod 24 is provided with a threaded connection with a member 105 34 having a lock nut 35 whereby the adjustment and extent of lost motion is made.

Figure 3 shows a flat adjusting rod which

may be used in place of the round adjusting rod 24, 26. This modification does not change the principle of operation of the combination as a whole. The part 39 is a guide box and the part 31' represents a friction housing in which are holding dogs and spring similar in principle of operation and similarly disposed to the adjusting rod as the dogs and spring in the housing 31 of the 10 round adjusting rod.

The operation of this device is substantially as follows:

On application of the brakes the piston 6 moves outwardly either by power from the 15 cylinder 5 or by pull rods connected with the hand brake mechanism. Pull rods for the hand brake mechanism are shown at 36, Figure 2, attached to extensions of the lugs on part 6. These parts, however, have been 20 omitted in Figure 1 in order to show more clearly the manner of connecting the opposite ends of the live lever. This movement is transmitted to the live and dead levers 8 and 12, the proper action and reaction 25 taking place by reason of connecting rod 37, Figure 2, against action of return spring 38. This movement tends to move ends of the live and dead levers 14 and 16 shown 30 in the lower part of Figure 1 toward each other, and as dogs 23 in housing 22 are in locked engagement against relative inward movement of rods 20, 21 there is a consequent outward movement of the opposite 35 ends of the levers 14 and 16 to force the brake beams 33 relatively apart. If no slack is to be taken up a pin 40 merely travels to the position shown in Figure 1 40 along the slot 25. Any subsequent movement of the pin, however, will cause a relative outward movement of the rod 24 toward the left with respect to its telescopic member 26, it being understood that this rod 24 is free to slip freely in that direction on application of the brakes. On release 45 of the brakes the pin 40 drops back its clearance distance as provided by the slot 25 under the action of return springs 28 and 38. The temporary take up and holding means within the housing 31 however prevent inwardly telescoping movement of the parts 24 and 26 under which 50 circumstances the points 40 and 27 act as fulcrums to cause a relative outward telescopic movement of the parts 20 and 21. In this manner the permanent take up and 55 holding means within the housing 22 is actuated to an extent exactly corresponding to the excess travel of the brake rigging.

It is thus seen that the present invention 60 provides a simple slack adjuster mechanism particularly adapted for use in connection with a foundation brake rigging.

Considerable variation of the details as 65 described herein may be resorted to without departure from the spirit of the invention

which is to be construed in the light of the following claims:

What I claim is:—

1. In a slack adjuster mechanism, in combination, a source of power, live and dead levers connected therewith, a second set of live and dead levers connected with said first set, brakes connected with said second set, telescopic push rod between said second set of dead levers, telescopic adjusting rod between said second set, positively acting means associated with both push rod and adjusting rod whereby telescopic movement of each is permitted in one direction. 70

2. In a slack adjuster mechanism, in combination, a source of power, live and dead levers connected therewith, a second set of live and dead levers connected with said first set, brakes connected with said second set, a telescopic push rod between said second set of dead levers, telescopic adjusting rod between said second set, positively acting means associated with both push rod and adjusting rod whereby telescopic movement of each is permitted in one direction, 80 and a lost motion device associated with one of said parts permitting normal brake shoe clearance. 35

3. In a slack adjuster mechanism, in combination, a source of power, live and dead levers connected therewith, a second set of live and dead levers connected with said first set, brakes connected with said second set, a telescopic push rod between said second set of dead levers, telescopic adjusting rod between said second set of dead levers, positively acting means associated with both push rod and adjusting rod whereby telescopic movement of each is permitted in one direction, 95 a lost motion device associated with one of said parts permitting normal brake shoe clearance, and spring means adapted to return said parts to normal position. 100

4. In a slack adjuster mechanism, in combination, a source of power, live and dead levers connected therewith, a second set of live and dead levers connected with said first set, brakes connected with said second set, a telescopic push rod between said second set of dead levers, telescopic adjusting rod between said second set of dead levers, positively acting means associated with both push rod and adjusting rod whereby telescopic movement of each is permitted in one direction, 110 a lost motion device associated with one of said parts permitting normal brake shoe clearance, and spring means adapted to return said parts to normal position, said spring means including a spring 115 associated with each set of live and dead levers. 120

5. In a slack adjuster mechanism, in combination, a source of power, live and dead levers connected therewith a push rod and 130

- return spring acting therebetween, a second set of live and dead levers connected with said first set, a push rod and return spring associated with said second set and an adjusting rod parallel to said push rod having a lost motion connection with one of said levers to insure brake shoe clearance.
6. In a slack adjuster mechanism, in combination, a source of power, live and dead levers connected therewith, a push rod and return spring acting therebetween, a second set of live and dead levers connected with said first set, a push rod and return spring associated with said second set, an adjusting rod parallel to said push rod having a lost motion connection with one of said levers to insure brake shoe clearance, said push rod and adjusting rod associated with the second set of live and dead levers, each having positively acting means permitting telescopic movement between the effective ends thereof.
7. In a slack adjuster mechanism, in combination, a source of power, live and dead levers connected therewith having push rod and return spring acting therebetween, a second set of live and dead levers connected with said first set, a push rod and return spring associated with said second set, an adjusting rod parallel to said push rod having a lost motion connection with one of said levers to insure brake shoe clearance, said push rod and adjusting rod associated with the second set of live and dead levers, each having positively acting means permitting telescopic movement between the effective ends thereof, said positively acting means including a housing associated with one part having holding dogs adapted to coact with the other part.
8. In a slack adjuster mechanism, in combination, a source of power, live and dead levers connected therewith, a push rod acting between the central part of said live and dead levers, a second set of live and dead levers connected at their ends with the ends of said first mentioned set, a two part telescopic push rod acting between the central parts of said second set of live and dead levers, an adjusting rod connected with said levers and lying parallel to said push rod, said adjusting rod comprising two telescopic parts and positively acting holding means acting with both said push rod and said adjusting rod adapted to permit a relative change in the effective length of each 55 in opposite directions.
9. In a slack adjusted mechanism, in combination, a source of power, live and dead levers connected therewith, a push rod acting between the central part of said live and dead levers, a second set of live and dead levers connected at their ends with the ends of said first mentioned set, a two part telescopic push rod acting between the central parts of said second set of live and dead 60 levers, an adjusting rod connected with said levers and lying parallel to said push rod, said adjusting rod comprising two telescopic parts, positively acting holding means coacting with both said push rod and said 65 adjusting rod adapted to permit a relative change in the effective length of the adjusting rod upon application of the brakes and of the push rod upon release of the brakes, and a lost motion device associated with said 70 adjusting rod adapted to permit normal brake shoe clearance and prevent actuation of the slack adjuster except when excess travel occurs.
10. In a slack adjuster mechanism, in combination, a source of power, live and dead levers connected therewith, a second set of live and dead levers associated with said first mentioned live and dead levers, a two-part telescopic push rod acting between the central parts of said second live and dead levers and positioned parallel to a two-part adjusting rod connected with said second live and dead levers, positively acting holding means 80 adjusted respectively to said adjusting rod 85 and to said push rod, whereby the effective length of said adjusting rod is changed when said first mentioned live and dead levers move their associated ends of the said second live and dead levers relatively apart and 90 whereby the effective length of said push rod is changed when said first mentioned live and dead levers move their associated ends of the said second live and dead levers relatively together.
- In testimony whereof I affix my signature in the presence of two witnesses.
